(57) **CLAIM**

The ornamental design for a handle for electric hair comb, as shown and described.

DESCRIPTION

FIG. 1 is a perspective view of a handle for electric hair comb showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof.

FIG. 9 is a perspective view of a handle for electric hair comb showing my new design where the handle for electric hair comb is in a first configuration of use;

FIG. 10 is a perspective view of the handle for electric hair comb where the handle for electric hair comb is in a second configuration of use; and,

FIG. 11 is a perspective view of the handle for electric hair comb where the handle for electric hair comb is in a third configuration of use.

The broken line attachments that are shown in FIGS. 9-11 illustrate the environment, while the remaining broken lines illustrate portions of the handle. None of the broken line disclosure forms part of the claimed design.
